[57] **CLAIM**

The ornamental design for an audio speaker cabinet, as shown and described.

DESCRIPTION

FIG. 1 is a front elevation view of an audio speaker cabinet, showing our new design;

FIG. 2 is a top plan view thereof;

FIG. 3 is a side elevational view thereof; and

FIG. 4 is an elevation as seen from the side opposite FIG. 3.

The undisclosed rear portions of the speaker cabinet are plain and unornamented.

FIG. 1

FIG. 2

FIG. 3

FIG. 4
